[57] CLAIM

The ornamental design for an electrical cord connector plug, as shown and described.

DESCRIPTION

FIG. 1 is a perspective view of the electrical cord connector plug showing my new design;

FIG. 2 is a top plan view thereof;

FIG. 3 is a front elevational view thereof;

FIG. 4 is an elevational view taken from the right side of FIG. 3, the left elevational view being a mirror image thereof;

FIG. 5 is a bottom plan view thereof;

FIG. 6 is a rear elevational view thereof;

FIG. 7 is a perspective view as seen from the rear and upper left of the plug; and,

FIG. 8 is a perspective view as seen from the rear and lower right of the plug.

The broken line showing in FIGS. 1 and 3 is included for the purpose of illustrating environmental structure only, and forms no part of the claimed design.
